ATTORNEY.

UNITED STATES PATENT OFFICE.

JOHN Z. BENSON, OF LAWN HILL, IOWA.

CORN-CRIB.

SPECIFICATION forming part of Letters Patent No. 458,936, dated September 1, 1891.

Application filed April 24, 1891. Serial No. 390,272. (No model.)

To all whom it may concern:

Be it known that I, JOHN Z. BENSON, of 5
Lawn Hill, in the county of Hardin and State
of Iowa, have invented a new and Improved
Crib-Door, of which the following is a full,
clear, and exact description.

My invention relates to improvements in
doors for corn-cribs and other granaries, and
which is also adapted for use on vehicles.

10 The object of my invention is to produce a
simple and convenient form of door which
may be adjusted so as to afford ventilation
for the crib or other building or vehicle in
which it is secured, which is adapted for ad-
15 justment to suit the various kinds of grain,
and which is constructed in such a manner
that it may be arranged so that the grain may
be easily removed.

To this end my invention consists in a door
20 constructed substantially as hereinafter de-
scribed and claimed.

Reference is to be had to the accompanying
drawings, forming a part of this specification,
in which similar figures of reference indicate
25 corresponding parts in all the views.

Figure 1 is a vertical section of a door em-
bodying my invention, showing the same ap-
plied to a crib. Fig. 2 is a broken front ele-
vation of the same, the door being open. Fig.
30 3 is a sectional view and shows the applica-
tion of the door to a wagon-body; and, Fig. 4
is a broken detail view of one of the slides.

The crib 10 is provided with the usual ver-
tical side walls 11, in one of which is set the
35 door-frame 12, which is arranged so that it
will project inward beyond the wall 11, and
this frame is provided with a swinging por-
tion 13, which is adapted to close the opening
through the frame, and which is substantially
40 like an ordinary door. On opposite sides of
the frame are vertical side pieces 14, which
are provided at intervals with inwardly-in-
clined grooves 15, in which fit slides 16, which
slides extend transversely between two side
45 pieces, and the grooves 15 in the said side
pieces are arranged so as to have different
inclinations, in order that the slides may be
adjusted according to the kind of grain that
is held in the crib, as will be hereinafter de-
50 scribed. The slides 16 are provided at the
ends and on their outer edges with projecting

shoulders 17, which extend beyond the edges
of the grooves 15, and thus prevent the slides
from dropping down through the grooves.

When the device is applied to a wagon- 55
body, the wagon 18 is provided with the usual
end-board 19, and the door is secured in the
wagon-body just forward of the end-board 19,
and it is obvious that the height of the door
should correspond approximately with the 60
depth of the wagon-body. The door may also
be applied to a railway-car, or it may be ap-
plied to any receptacle adapted to hold grain.

The door is used in the following way: The
lower slides of the frame are preferably ar- 65
ranged in the grooves having the greatest in-
clination, so that the bottom slide will rest on
the bottom of the crib and prevent any of the
grain from running out, and the slides above
are arranged in the grooves of the greatest 70
inclination or in those of less inclination, ac-
cording as the grain is fine or coarse, as it is
obvious that it will be necessary to give them
great inclination where the grain is fine, as
otherwise it will work through between the 75
slides and run to waste. It will be seen by
reference to Fig. 1 that there is an air-space
between the several slides, and when the crib
is filled with the grain the air will pass in-
ward between the slides and into the crib, so as 80
to ventilate the same, and the inclination of
the slides will prevent the grain from running
out between them. When a small portion of
grain is to be removed from the crib, one of
the slides is drawn out and a portion of the 85
grain is allowed to run into a receptacle which
may be arranged to receive it, and if the grain
is to be shoveled out one or more of the bot-
tom slides are removed, and the grain may
then be easily shoveled up from the floor. 90

Where the door is to be used in a wagon-body
or in a car, the operation is substantially the
same. When the door is to be used for ven-
tilating purposes, the swinging portion 13 is
thrown open, so that the air may pass freely 95
between the slides.

Having thus fully described my invention,
I claim as new and desire to secure by Letters
Patent—

1. The combination, in a crib-door, with the 100
door-frame having on its sides inclined
grooves open from end to end to prevent the

lodgment of grain, of slides fitting in the grooves and provided at their outer corners with shoulders projecting beyond the grooves to limit the inward movement of the slides, 5 substantially as set forth.

2. The combination, in a crib-door, with the door-frame having series of inclined grooves, the grooves of one series extending at a dif-

ferent angle from those of the other series, of a series of slides adapted to fit the grooves of either series, according to the character of the grain, substantially as set forth.

JOHN Z. BENSON.
